UNITED STATES PATENT OFFICE

123,270

DESIGN FOR A CLAMP APPLYING TOOL

Holbrook Mahn, Denver, Colo.

Application July 29, 1940, Serial No. 93,995

Term of patent 7 years

To all whom it may concern:

Be it known that I, Holbrook Mahn, a citizen of the United States, residing at 200 Santa Fe Drive, in the city and county of Denver and State of Colorado, have invented a new, original, and ornamental Design for Clamp Applying Tools, of which the following is a specification, reference being had to the accompanying drawing, forming part thereof.

In the drawing:

I claim:

The ornamental design for a clamp applying tool, as shown,

HOLBROOK MAHN.
